UNITED STATES PATENT OFFICE.

ERNEST A. WALKER, OF NEWARK, NEW JERSEY, ASSIGNOR TO ARTCRAFT FIXTURE COMPANY, OF NEWARK, NEW JERSEY, A CORPORATION OF NEW JERSEY.

DESIGN FOR AN ARM FOR LIGHTING-FIXTURES.

57,957.

Specification for Design.

Patented May 17, 1921.

Application filed October 16, 1920. Serial No. 417,497. Term of patent 7 years.

To all whom it may concern:

Be it known that I, ERNEST A. WALKER, a citizen of the United States, residing at Newark, in the county of Essex and State of New Jersey, have invented a new, original, and ornamental Design for an Arm for Lighting-Fixtures, of which the following is a specification, reference being had to the accompanying drawing, forming part thereof.

Figure 1 is a side elevation of the arm for lighting fixture.

Fig. 2 is a front view of the arm for lighting fixture.

Fig. 3 is a bottom or end view of the arm for lighting fixture.

I claim:

The ornamental design for an arm for lighting fixtures, as shown.

ERNEST A. WALKER.
